Patented Aug. 7, 1928.

UNITED STATES PATENT OFFICE.

RAYMOND R. MACHLETT, OF NEW YORK, N. Y., ASSIGNOR TO RAINBOW LIGHT, INC., OF LONG ISLAND CITY, NEW YORK, A CORPORATION OF NEW YORK.

LUMINOUS TUBE AND PROCESS OF MANUFACTURING THE SAME.

Application filed November 17, 1927. Serial No. 233,772.

My present invention relates to an improved luminous discharge tube and to an improved process of manufacturing the same. The improved tube is of the type in which interior electrodes are used and which contains a rarefied atmosphere comprising an inert gas, such as neon. Argon, helium or other so-called noble gas may be used either alone or in combination, and mercury vapor in minute quantity may be employed in conjunction therewith in order to increase the range of colors.

The pressure of the gas is such that it will become luminous under the effect of an electrical discharge. With neon, for example, although the pressure at which maximum conduction occurs is in the neighborhood of 1 m. m. of mercury absolute, yet initial pressures in the neighborhood of 8 to 10 m. m. are preferred, since in this way the life of the tube may be enormously increased without necessitating the employment of prohibitively long tubes.

With my improved luminous tube it is possible to employ electrodes which are of very small size, and hence can be more cheaply manufactured and installed. These small electrodes also enable the tube to be made with end portions which are not unduly large and cumbersome. This feature of the invention is particularly valuable in connection with tubes of large size, such as a neon beacon, in which very heavy currents are employed.

When ordinary interior electrodes are used it is important that the current density should be such as not to increase the normal cathode drop of potential, and this means that the negative glow should not extend further than to just encompass the electrode surface. If the current density is increased beyond this normal value, a very great rise in the cathode drop takes place accompanied by heating, and the phenomenon of sputtering or vaporization becomes much more pronounced with an accompanying depletion of the conducting atmosphere, a reduction in the pressure, and eventually in the failure of the tube to conduct. The life of the tube is thus shortened.

I have found that with ordinary interior electrodes the critical area at which the normal cathode drop tends to become abnormal is between 10 and 14 sq. decimeters per am-

pere of current with neon gas at a pressure of $7\frac{1}{2}$ m. m. of mercury. As the pressure of gas is diminished the critical electrode area becomes larger and, therefore, it is the practice to make the electrodes substantially larger than the critical value at the pressure of gas employed, in order that, as the pressure is reduced, the normal cathode drop may still be maintained. It would not be commercially practicable to make the electrodes sufficiently large to maintain the normality of the cathode drop with the gas at the minimum pressure when conduction has ceased, because to do that would involve the use of electrodes of enormous size.

Commercial practice, therefore, is in the nature of a compromise, the electrodes being substantially larger than the critical area referred to, in order to take care of a substantial reduction of pressure representing the greater part of the life of the tube. Then, as the pressure tends to still further decrease, there will be a gradual increase in the cathode drop representing further useful life. The final hours of the tube will be those in which the sputtering becomes very violent, since this phenomenon is greatest at low pressures.

By means of my invention I am enabled to make a luminous tube in which the electrode area is many times smaller than that required by the classical rules of current density, so that a neon beacon, for example, can be made and operated with currents of from 5 to 10 amperes or more and yet the electrodes will be of relatively small size. This is an extremely important consideration in the commercial manufacture of very large luminous tubes where the employment of ordinary interior electrodes might involve the use of glass chambers several feet long and a foot or more in diameter.

The method which I have developed for making these tubes is a specific improvement on the process disclosed in my Patent, No. 1,618,767, dated February 22, 1927. With the patented process I am enabled to obtain a luminous tube in its complete final state of purity directly from the pumping apparatus and without the necessity of further aging or seasoning, thereby securing a substantial saving of time of manufacture. With my present method I employ the same fundamental idea disclosed in said patent,

of utilizing a purging agent prior to the admission of a pure gas to the tube, but I have modified the process in certain respects to be hereafter described, by which the operations 5 may be carried out with greater facility and a great saving of time will be effected.

While the improved process is especially intended for use in the manufacture of luminous tubes having interior electrodes and 10 finds its greatest value in this field, yet it may be employed in the manufacture of tubes having exterior electrodes.

My objects generally are to provide an improved luminous tube of high efficiency and 15 long life and employing electrodes of relatively small size and to provide a process by which such tubes may be economically manufactured, all as I will hereafter described and claim.

20 In order that the invention may be better understood attention is directed to the accompanying drawing, in which

Figure 1 is a perspective view of a suitable oven for processing the tubes, showing three 25 tubes therein, the front of the oven being elevated to disclose its interior; and

Figure 2 a side elevation on a somewhat larger scale, showing a single tube in process of manufacture.

30 In both of these views corresponding parts are represented by the same numerals.

1 represents the improved luminous tube which is shown as having a straight central portion and enlarged ends 2-2, made preferably of boro-silica glass having a high melting point, as disclosed in said patent. It will be understood, of course, that the shape of the tube is unimportant.

40 The enlarged chambers 2-2 of the tube are formed with inwardly-extending necks 3, in which are sealed the conductors 4-4 leading to the electrodes 5-5. Each electrode is supported upon a neck or tube 6 made preferably of quartz.

45 The electrodes 5-5 are made of a conducting material having the property of occluding or absorbing substantial amounts of the alkali vapor admitted to the tube, as I will hereafter describe. I have found that 50 graphite or other forms of carbon are admirably suited for the purpose.

The surface area of the electrodes is relatively small, and I have in practice made use of graphite electrodes having a surface 55 area as low as .6 decimeters per ampere of current with neon gas at a pressure of 7½ m. m. of mercury. Electrodes of this size give excellent results and remain cool in operation, at least for most of the life of the 60 tube, which may be several thousand hours.

In processing the improved tubes a number of them are mounted side by side and secured together by tubulations 7 leading to a common tube 8 and supported by hangers 65 9 within a suitable oven 10. For the purpose

of illustration I show three of these tubes 1 in the oven 10, although the number may be more or less. By thus simultaneously processing a plurality of tubes, I very greatly extend the capacity of the ovens and reduce 70 the time required to perform the necessary operations. With the method disclosed specifically in my patent above referred to, one tube at a time is processed and the operation further involved the carrying out of 75 the steps which I am now able to dispense with, as I will describe.

The oven 10 is heated in any suitable way, such as by means of gas jets 11 located below a perforated partition 12. It is also provided with a door 13 capable of being lifted up and down or otherwise opened and closed, and said door is provided with one or more sight openings 14 therein covered with mica, in order to permit the tubes within the oven 85 to be observed.

A tubulation 15 depends from each tube preferably near its centre and contains a small quantity 16 of an alkali metal, the vapor of which is to be employed as the 90 purging agent.

The tube 18 extends through one of the side walls of the oven and leads to suitable pumping apparatus as indicated. This may be of any suitable and approved type. In 95 my patent I have indicated more specifically a desirable arrangement.

The tube 8 is also provided with a branch tube 15 leading to a suitable gas supply, such as neon. Valves 16 and 17 are shown to cut off the tubes which are being processed from the pumping apparatus or gas supply as may be needed.

The conductors 4 are shown in Figure 2 as being connected to the secondary 18 of 105 a transformer, the primary 19 of which is in circuit with a suitable source of alternating current 20. All of the tubes have similar electrical connections and their conductors 4 may be connected in multiple with 110 a single secondary 18, as will be obvious.

Assuming that the tubes are supported within the oven, as shown in Figure 1 and that the door 13 is closed, the process is carried out as follows:

115 The pumping apparatus being started, air will be exhausted simultaneously from all the tubes. When the pressure has been sufficiently reduced all the electrodes in the tubes are strongly heated by the passage of 120 a heavy current through the same. The effect of thus heating the electrodes is to drive off gases occluded therein and to activate the carbon of which they are composed, so as to make it strongly susceptible 125 to the occlusion of the alkali metal vapor when this is provided. The current which is employed for thus activating the electrodes is substantially greater than the normal value of the current with which the tube is 130

designed to operate under practical conditions. Thus, the normal current in operation will not tend to drive off undesirable impurities.

5 During the next stage of the process the several tubes are slowly heated in the oven until a temperature is reached at which the alkali metal 16 in each of the tubulations 15 gives off vapor which permeates the several 10 tubes. The temperature to which the tubes are heated depends upon the alkali metal used and may vary approximately between 200 and 500 degrees centigrade. When caesium is used, as is preferred, the temperature 15 is not so high as when potassium or sodium is employed. It is only necessary that the temperature shall be sufficient to vaporize the alkali metal and cause it to diffuse into the several tubes. The step thus described 20 will be recognized as an improvement over the specific disclosure of my patent, where the vaporization of the alkali metal was effected by heat applied exteriorly of the oven. The diffusion of the alkali vapor 25 through the tubes causes it to be occluded or absorbed to a marked degree in the carbon or graphite of the electrodes.

Concurrently with the diffusion of the alkali metal through the tubes, a potential is 30 applied to the electrodes sufficient to cause a current of approximately normal value to flow through each tube and the progress of the vapor through the tube may be observed by the fact that its characteristic light 35 proceeds along the tube. This diffusion of the alkali vapor through the several tubes takes place as the pumping continues and eventually each tube will be filled with the alkali vapor, relatively large volumes of which 40 will be occluded or absorbed in the carbon or graphite electrodes. By thus subjecting each tube to the action of alkali vapor all impurities will be removed from the tube 45 walls and the electrodes, the operations being continued until a spectroscopic examination discloses no impurities but only the spectrum of the alkali vapor.

After the vapor has been thus diffused through the tubes the heating is discontinued 50 and the tubes are allowed to cool. The passage of the current is also discontinued. As soon as the oven temperature has dropped sufficiently low, the several tubulations 15 are sealed off so as to arrest the supply of 55 alkali metal vapor and the pumping continues thereafter until substantially all traces of the vapor have been drawn off from the tubes. Any residual vapor remaining in the tubes will be too slight to have any 60 effect on the color or electrical characteristics of the tube.

The valve 16 is now closed to cut off the pump and the valve 17 is opened to permit the introduction into all the tubes of neon 65 or other rare gas at the desired pressure,

which is preferably in the neighborhood of 8 to 10 m. m. of mercury. Thereafter the tubulation 7 of each tube is sealed off and the tube is then ready for use without sealing or aging.

When caesium is the alkali metal which is to be used, it not only acts as an effective purging agent to free the tubes of all deleterious impurities, but, when it is occluded in the absorbent electrodes, it results in a tube having extremely desirable electrical characteristics. Those characteristics are substantially those which take place when caesium is vaporized to form a mirror in the neighborhood of the electrodes (specifically the cathode) as I describe in my application for Letters Patent, Serial No. 142,839, filed October 20, 1926. In other words, the occluded caesium vapor in the electrode permits me to make use of an electrode of extremely small size without detracting from the life of the tube or its efficiency in operation. Furthermore, as when a caesium mirror is used, the electrodes having caesium occluded therein result in an alteration in the distribution of energy in the tube, so as to obtain an increase of ohmic resistance in the gaseous column relative to the total resistance of the tube and thus a more effective application of energy is secured for illuminating purposes.

It will be seen that if the tubes 1 are provided with exterior electrodes instead of interior electrodes they may be processed in accordance with the procedure described above and with the same advantages as to facility of operation and saving of time.

A number of such tubes can be processed at once and the alkali metal vapor will be diffused therein automatically, as the result of merely heating the tubes in the oven, thus doing away with the special exterior treatment disclosed in my said patent.

Having now described my invention what I claim as new therein and desire to secure by Letters Patent is as follows:

1. An improved luminous tube, comprising a transparent tubular container having therein a rare gas of the atmosphere under reduced pressure, and interior electrodes within the tube of absorbent conducting material having an alkali metal vapor occluded therein, substantially as set forth.

2. An improved luminous tube, comprising a transparent tubular container having therein a rare gas of the atmosphere under reduced pressure, and interior electrodes within the tube of carbon having an alkali metal vapor occluded therein, substantially as set forth.

3. An improved luminous tube, comprising a transparent tubular container having therein a rare gas of the atmosphere under reduced pressure, and interior electrodes within the tube of graphite having an alkali

- metal vapor occluded therein, substantially as set forth.
4. An improved luminous tube, comprising a transparent tubular container having therein a rare gas of the atmosphere under reduced pressure, and interior electrodes within the tube of carbon having caesium vapor occluded therein, substantially as set forth.
- 10 5. An improved luminous tube, comprising a transparent tubular container having neon therein under reduced pressure, and interior electrodes within the tube of carbon having an alkali metal vapor occluded therein, substantially as set forth.
- 15 6. An improved luminous tube, comprising a transparent tubular container having neon therein under reduced pressure, and interior electrodes within the tube of carbon having caesium vapor occluded therein, substantially as set forth.
- 20 7. An improved luminous tube, comprising a transparent tubular container having therein a rare gas of the atmosphere under reduced pressure, and interior electrodes within the tube of carbon having an alkali metal vapor occluded therein, the area of each of said electrodes being less than one square decimeter per ampere of normal current at a gas pressure of $7\frac{1}{2}$ m. m. of mercury, substantially as set forth.
- 25 8. An improved luminous tube, comprising a transparent tubular container having neon therein under reduced pressure, and interior electrodes within the tube of carbon having an alkali metal vapor occluded therein, the area of each of said electrodes being less than one square decimeter per ampere of normal current at a gas pressure of $7\frac{1}{2}$ m. m. of mercury, substantially as set forth.
- 30 9. An improved luminous tube, comprising a tubular container having neon therein under reduced pressure, and interior electrodes within the tube of carbon having caesium vapor occluded therein, the area of each of said electrodes being less than one square decimeter per ampere of normal current at a gas pressure of $7\frac{1}{2}$ m. m. of mercury, substantially as set forth.
- 35 10. The method of processing luminous tubes containing carbon electrodes and having a tubulation containing caesium, which consists in creating a partial vacuum in the tube, in passing a heavy current between said electrodes so as to activate the same, and in subjecting the tube and tubulation to the effect of heat by which under the reduced pressure caesium vapors will be evolved so as to permeate the tube and become occluded in the carbon electrodes, substantially as set forth.
- 40 11. The method of processing luminous tubes having interior carbon electrodes and provided with a tubulation containing caesium, which consists in passing a heavy current between the electrodes to activate them, in creating a partial vacuum within the tube and tubulation, in subjecting both the tube and tubulation to a heated atmosphere, whereby under the reduced pressure caesium vapors will be evolved and will be diffused through the tube and become occluded in the electrodes, and in passing a current of substantially normal value between the electrodes before sealing off the tubulation until under the spectroscope the spectrum of caesium is alone visible, substantially as set forth.
- 45 12. The method of processing luminous tubes containing interior electrodes of carbon and provided with a tubulation containing caesium, which consists in creating a partial vacuum within the tube and tubulation, in then activating the electrodes, in then subjecting the tube and tubulation to the effect of heat, whereby under the reduced pressure caesium vapor will be evolved and will be diffused through the tube so as to be occluded in the electrodes, in maintaining a current of substantially normal value within the tube, before sealing off the tubulation, said current being maintained until the pure caesium spectrum is alone visible, in then reducing the temperature of the tube and continuing the exhaustion so as to remove substantially all of the free vapor within the tube and in finally admitting the desired rare gas within the tube, substantially as set forth.

RAYMOND R. MACHLETT.
